1

This invention concerns welt rod mechanism for Cotton's patent and other straight bar knitting machines. It is known in the production of fashioned blanks for women's stockings on a straight bar knitting machine, to draw the initial courses of the fabric away from the needle by means of a welt bar having welt hooks or welt instruments engaged with thread kinks of the set-up course, to place a welt stick or welt rod on the fabric by hand and to engage the ends of the stick or rod with draw-off straps, and then to manipulate the welt bar by hand to transfer the kinks of the set-up course from the welt hooks to the needles (the welt hooks being subsequently disengaged from the fabric) so that the welt stick or rod reposes in a loop of the welt fabric; the fabric of the leg is thereafter drawn away from the needles by a pull applied to the rod or stick by the straps. Proposals have been made in connection with Cotton's patent and other straight bar knitting machines having automatic welt turning mechanism, for the provision of means whereby a single welt stick may be temporarily held above the level of the fabric and lowered to the fabric at the appropriate time for engagement by the hooks on the straps. These proposals involve the insertion of the single stick into suitable supporting means by hand and, in the case of a machine incorporating several divisions or sections, these proposals would involve the operator moving along the machine and inserting a single stick into the supporting means at each division.

The object of the present invention is the provision of improved welt stick or welt rod mechanism in which there is a magazine into which several sticks or rods may be loaded and single sticks thereafter being delivered from the magazine at the appropriate time and employed each in the manufacture of a single stocking blank.

Therefore the present invention in a Cotton's patent or other straight bar knitting machine having welt turning mechanism and draw off straps (or their equivalent flexible means such as cords, all of which will, in the appended claims, be comprehensively denoted by the term "bands") equipped with hooks for engaging the ends of a welt rod or stick to draw the fabric away from the needles, the combination of a magazine for a plurality of welt rods and means for effecting the delivery of a single rod from the magazine at the appropriate time in the manufacture of each stocking blank and for presenting it above the fabric at a position to be engaged by the draw-off hooks. Preferably the magazine is dis-

posed in front of the needle line (i. e. towards the front of the machine and at the side of the needles opposite the needle beards) and the straps are arranged to carry the delivered rod rearwards from the magazine towards the needle line, in reverse movement of the straps, to a ready station in which the rod awaits engagement by the hooks in draw-off movement of the straps. This permits the magazine to be disposed at a location such that it and its contained pile of sticks will not obstruct the operator's view of the knitting needles and their adjacent co-operating elements.

It is preferred to provide means for holding the rod, presented at the ready station, at a position above the welt instruments (such instruments being provided on a welt bar) during the production of the initial courses of the welt fabric and for lowering it after the passage of the welt instruments from beneath it. This arrangement ensures that the welt rod descends on to the fabric itself and not on to the welt instruments. It also assists in ensuring that when this lowered rod is engaged by the draw-off hooks, the rod can pass below the welt instruments to draw a bight of welt fabric beneath the latter.

This invention further provides in a straight bar knitting machine having flexible draw-off straps equipped with hooks for engaging the ends of a welt rod to draw the fabric away from the needles in a draw-off movement of the straps, said straps being movable in the reverse direction preparatory to the draw-off movement, a welt rod magazine, for the reception of a pile of rods above the straps, disposed in front of the needle line, said magazine having a mouth through which the rods may be loaded into it, guides for receiving the ends of a welt rod discharged from the base of the magazine and for guiding said rod to a ready station, near the needle line, in which the rod is disposed to be engaged by the hooks on draw-off motion of the straps, and catch mechanism, operable on reverse movement of the straps, for releasing a single rod from the magazine onto the straps for conveyance by the latter along the guides to the ready station.

The invention is broadly applicable to Cotton's patent or other straight bar knitting machines having welt turning mechanism of the type wherein the welting instruments mounted on a welt bar are inserted from the front or plain side of the needles to receive the thread loops or kinks of an initial welt course, are subsequently retracted during the knitting of part of the welt,

and finally advanced to the needles to restore or offer the said loops or kinks to the needles.

In the accompanying drawings:

Figure 1 is a sectional elevation of the machine (showing sufficient of it to permit it to be identified) and of the welt rod mechanism;

Figures 2, 3 and 4 are sections, on a large scale, through the magazine and associated parts showing three successive stages in the release of a rod;

Figure 5 is an elevation and,

Figure 6 is a perspective view of one end of the magazine;

Figure 7 is a perspective view of a trigger at the left hand end of the magazine.

For the purpose of identifying the machine, reference is invited in Figure 1 to the needles 1, sinkers 2, knocking-over bits 3, jacks 4, slur-cock 5, sinker bed 6, sinker cap 7, machine frame members 8 and 8', and catch bar 9; these and other parts of the machine are of conventional character and need no further description or illustration herein, but additionally attention is directed to welt bar 11 (with welt hooks 12), draw off straps 18 with hooks 55, rollers 56, 57, 58, for said straps, welt sticks 17, and welt stick guides 53 with stick-receiving grooves 54.

In describing a preferred construction according to this invention it is desirable for the sake of simplicity to consider the mechanism provided for a single division or section of a multidivisional machine, or the mechanism provided for a "single head" machine.

The magazine 42 is disposed at a location near the front of the table 8' of the machine, slightly rearwards and above the usual take-up roller 57 to which the two take-up straps 18 are attached and on which the stocking blank is wound up as it is knitted. The magazine comprises, in the main, end members 13 at opposite ends of the division and each formed with a vertical slot 14 at its inner face. These slots 14 are arranged to receive the ends of a series of welt rods 17 disposed in them one above the other, and are open at the top to provide a mouth through which the rods may be loaded into the magazine. The discharge of the welt rods, one by one, as hereinafter described, is controlled by triggers 19 which are pivoted one on each member 13. Each trigger 19 depends from its pivot 20 at the front of the rods 17 and has a protrusion 21 or slot which underlies the lowermost rod. It will be appreciated that when this trigger 19 is swung rearwards (i.e. towards the needles 1) the rods are released, but in order to prevent all rods other than the lowermost rod from falling down out of the slots, the trigger is provided with a detent 22 which, when the trigger is swung rearwards, itself moves rearwards and enters beneath the lowermost rod but one. As illustrated in Figure 3, when the trigger 19 swings forward again, under the influence of spring 23 the protrusion 21 passes beneath the rod 17 next above that just released (as shown in Figure 4) so that said next rod (and every rod above it) is prevented from falling down the slots 14.

It will therefore be appreciated that this mechanism provides means whereby each time the triggers 19 are swung rearwards, a single rod is released to fall down from the magazine 42. This rod 17 enters a groove or channel 54 cut in the inner face of each guide 53, being there disposed beneath an inturned tail 24 on the lower end of each trigger.

It may here be mentioned that the two triggers 19 are formed right and left hand, but all details

of the right hand trigger will be obvious from the illustration of the left hand one in Figure 7.

The take-up straps 18 extend from the take-up roller 57 to a further roller 58 located just in front of the needle line and below the path of movement of the welt bar 11, and then extend down around the latter. After the production of a stocking blank and before the start of the next blank, the straps are unwound from the take-up roller 57 and are drawn over the roller last mentioned, either by operation of this last mentioned roller or by operation of some other strap-engaging device. This movement carries draw-off hooks 55 on these straps to a ready position (Figure 1) in which they are disposed adjacent to the lower part of the periphery of the second mentioned roller 58. Specifically, the straps may be wound by hand (e. g. by handle 33) onto the roller 56 and the latter retained in its wound-up condition, by means of a manually-releasable pawl 25 acting on ratchet wheel 26, in opposition to suitable draw-off force acting on roller 57. For example this draw-off force may be supplied by a weight 27 attached to cord 28, which latter extends over pulley 29 to a drum 30 on or connected to roller 57.

The reverse movement of the straps 18 and of the hooks 55 is also employed to effect discharge of the lowermost rod 17 from the magazine 42 and to carry that rod rearwards to the ready position in proximity to the needle line. The discharge of the lowermost rod is effected by the hooks 55 themselves which (as will be seen from Figure 3) engage the tails 24 of the triggers 19 and swing the latter rearwardly so that the rod falls on to the straps 18 in front of the hooks 55. The rod is carried rearwards on the straps by a cam-shaped protrusion 31 on the upper surface of each strap.

As the straps 18 travel towards the needle line, the rod 17 is carried with them by these protrusions 31, along the guide tracks 54. These tracks 54 are slightly upwardly inclined towards the needle line (it being noted that they intersect the general plane on which the straps 18 travel to and from the needle line) but in the vicinity of the top of the second roller 58 they turn vertically upward as shown on Figure 1. The cam-shaped members 31 operate to propel the rod along these tracks 54 and finally to raise it into the upward extremities 54' of the latter. This is the ready position of the rod and in this attitude the cam-shaped members 31 come to a standstill with the rod resting on them (Figure 1).

The rod thus presented at the ready position is held above the level of the welt bar 11 and welt instruments 12, thus permitting the latter to be advanced beneath it towards the needles 1 so as to take loops or kinks of the set-up course. Desirably however, at each end of the welt bar 11 the latter is equipped with a curved guard 32 which extends towards the needle line for at least the length of the welt instruments and so ensures that, irrespective of the position of the cam-shaped projections 31, the welt rod 17 at the ready position is held safely at a level above the welt instruments 12, both as the instruments advance to the needles 1 to take the set-up course and as they are withdrawn from the needles during the production of the first part of the welt.

At an appropriate stage in the movement of the welt bar 11 and instruments 12 away from the needle line, the take-up roller 57 is caused to rotate (e. g. by release of pawl 25) so that the take-up straps 18 are drawn away from the

needle line. This causes the cam shaped projections 31 to be moved from beneath the welt rod 17 presented at the ready position. The rod descends on to the welt fabric and immediately afterwards is engaged by the draw-off hooks 55. The latter, travelling away from the needle line as the straps are moved, draw the welt rod away from the needles and owing to the shape of the guides 54 for the ends of the rod, the rod is drawn downwards slightly. It thus draws a bight of welt fabric beneath the welt instruments 12 which at this time have come to a standstill. The welt instruments 12 are thereupon advanced to the needles 1 to offer or restore the kinks or loops of the set-up course to the needles, and are subsequently disengaged from these loops or kinks.

As the straps 18 continue to be wound onto the take-up roller 57, the welt rod 17 continues to move along guides 54 away from the needles 1 during the production of the remainder of the stocking blank, and eventually the welt rod passes around the take-up roller in the usual manner.

When the stocking blank has been completed and has been pressed off, the blank and its welt rod 17 is unwound from the take-up roller 57, and at the next rearward movement of the straps 18 preparatory to knitting the next blank a further welt rod is released from the magazine 42.

It will be appreciated that in a straight bar knitting machine having more than one division of needles, mechanism as aforesaid is provided for each division, it being desirable however to place all or a group of the take-up rollers 57 on a common shaft 34 for rotation by a common device such as 27, 28, 29, and to place all or a group of the rollers 56 on a common shaft 35 to be wound up by a common handle 33 and to be retained by a common detent 25, 26.

What I claim is:

1. In a straight bar knitting machine having a straight line of needles and welt forming instruments associated therewith, the combination of flexible draw-off bands equipped with hooks for engaging the ends of a welt rod, means to move the bands in directions towards and away from the needles, a magazine to accommodate a pile of welt rods situated above the bands and disposed in front of the needle line, guides situated below the magazine and extending towards the needle line, there being one such guide for each end of a rod and both of them open to receive a rod-end upon discharge of a rod from the magazine, means on the straps to engage a rod thus located in the guides and to move it towards the needles to a ready position when the straps are moved in the appropriate direction, and catch mechanism associated with the discharge of the magazine and comprising release means actuated by cooperation with the bands as they are so moved.

2. Apparatus comprising the combination according to claim 1, in which the means to move a rod towards the ready position comprises abutments carried by the bands to engage behind the rod-ends to carry the rod to the ready position, said abutments having cam surfaces which serve to raise the rod as it arrives at that position and when movement of the bands is reversed leave the rod and allow it to be lowered towards the fabric.

3. Apparatus comprising the combination according to claim 1, wherein the guides terminate, at their ends adjacent the needle line, in upwardly directed slots which arrest further movement of the rod towards the needles dur-

ing movement of the straps in an appropriate direction but permit it to move upwardly away from the fabric, and the straps carry camming abutments which engage behind the rod to propel

5 it to the upwardly directed slot whereupon continued movement of the straps in the same direction causes the abutments to force the rod upwardly by cam action and thus raise it above the fabric and welt forming instruments, movement of the straps in the opposite direction enabling the rod first to drop into the welt formation and thereafter to be engaged by the hooks by which draw-off of the fabric is then effected.

10 4. In a straight bar knitting machine having a straight line of needles, the combination of welt-forming instruments, flexible draw-off bands equipped with hooks for engagement with a welt rod, a magazine to accommodate a plurality of welt rods and so situated as to deposit a rod on to the draw-off bands in front of the needles, means to move the draw-off bands in opposite directions towards and away from the needles, and means carried by the bands and engageable with a deposited rod during movement of the bands towards the needles to carry such rod to a ready station above the fabric, said draw-off bands being adapted to engage such rod by means of their hooks during movement in the opposite direction away from the needles.

15 5. In a straight bar knitting machine having a straight line of needles, the combination of welt-forming instruments, flexible draw-off bands equipped with hooks for engagement with a welt rod, a magazine to accommodate a plurality of welt rods and so situated as to deposit a rod on to the draw-off bands in front of the needles, means to move the draw-off bands in opposite directions towards and away from the needles, and means secured to the bands and engageable with a deposited rod during movement of the bands towards the needles to carry such rod to a ready station above the fabric, said last mentioned means serving during movement of the draw-off bands in the opposite direction to leave the said rod in a position to be picked up by the hooks of the draw-off bands whereby such rod is drawn with the fabric away from the needles.

20 6. In a straight bar knitting machine having a straight line of needles, the combination of welt-forming instruments, flexible draw-off bands equipped with hooks for engagement with a welt rod, a magazine to accommodate a plurality of welt rods and so situated as to deposit a rod on to the draw-off bands in front of the needles, means to move the draw-off bands in opposite directions towards and away from the needles and means carried by the draw-off bands which last mentioned means, when it is moved towards the needles, will first engage a rod released from the magazine and will carry it to a ready station above the fabric and then operate to raise the rod above the welt forming instrument, and on the return movement of the draw-off bands will lower the rod into a position to be engaged by the hooks of the draw-off bands.

25 7. In a straight bar knitting machine having a straight line of needles, the combination of welt forming instruments, flexible draw-off bands equipped with hooks for engagement with a welt rod, a magazine to accommodate a plurality of welt rods and so situated as to deposit a rod on to the draw-off bands in front of the needles, means to move the draw-off bands in opposite directions towards and away from the needles, and means carried by the draw-off bands at a

position thereon spaced from the hooks in the direction of movement of the bands, which last mentioned means, when it is moved towards the needles, will first engage a rod released from the magazine, and will carry it to a ready station above the fabric and then operate to raise the rod above the welt forming instrument, and on the return movement of the draw-off bands will lower the rod into a position to be engaged by the hooks of the draw-off bands to draw it and the fabric away from the needles.

8. In a straight bar knitting machine having a straight line of needles, the combination of welt turning instruments, flexible draw-off bands equipped with hooks for engagement with a welt rod, a magazine to accommodate a plurality of welt rods, guide tracks to engage opposite ends of a welt rod and extending between the magazine and a ready station spaced from the magazine and situated above the fabric as it first leaves the needles, means to deliver the rods one at a time to said guide tracks to be conducted along them to the ready station, means on the draw-off bands to engage a rod released from the magazine, and means to move the draw-off bands to cause a released rod to be carried to the ready station and afterwards to cause the hooks to engage such rod in the neighborhood of the ready station and draw the rod and the fabric away from the needles.

9. In a straight bar knitting machine having a straight line of needles, the combination of welt turning instruments, flexible draw-off bands equipped with hooks for engagement with a welt rod, a magazine to accommodate a plurality of welt rods, catch mechanism associated with the magazine for releasing one rod at a time, means to deliver a rod released by the catch mechanism to the fabric in front of the needles and in such a position as to be engageable by said hooks, and means to move the draw-off bands in op-

posite directions towards and away from the needles to cause the hooks in the last mentioned movement to draw the rod and the fabric away from the needles, said catch mechanism including an actuating member disposed in the path of the hooks aforesaid whereby the said hooks operate the catch mechanism as the hooks are advanced towards the needles.

10. In a straight bar knitting machine having a straight line of needles, the combination of welt turning instruments, flexible draw-off bands equipped with hooks for engagement with a welt rod, a magazine to accommodate a plurality of welt rods, catch mechanism associated with said magazine for releasing one rod at a time, said catch mechanism comprising trigger devices for opposite ends of the rods whereof each trigger device is movable between rod-retaining and rod-releasing attitudes and each has a stop normally engaged under a rod in the retaining attitude, which stop is disengaged from the rod in the releasing attitude, means to deliver a rod released by the catch mechanism to the fabric in front of the needles and in such a position as to be engageable by said hooks, and means to move the draw-off bands to cause the hooks to draw the rod and the fabric away from the needles, said catch mechanism including also a detent which enters above a rod about to be released as the trigger devices are moved into the releasing attitude.
